United States Patent Office

Des. 218,866
Patented Sept. 29, 1970

218,866

DISPLAY STAND

Paul G. Schwesinger, Akron, Ohio, assignor to Locke
Manufacturing Company

Filed May 23, 1969, Ser. No. 17,301

Term of patent 14 years

Int. Cl. D6—01

U.S. Cl. D80—9

FIG. 1

FIG. 2

FIG. 4

FIG. 3

FIG. 5

FIG. 1 is a perspective view of a display stand showing my new design;

FIG. 2 is an elevational view taken from the left side thereof;

FIG. 3 is an elevational view taken from the right side thereof;

FIG. 4 is a top plan view thereof; and

FIG. 5 is a front elevational view thereof.

The broken line representation of merchandise in FIG. 1 is for purposes of illustration only.

I claim:

The ornamental design for a display stand, as shown and described.
